UNITED STATES PATENT OFFICE.

JOHN T. DEES, OF GOLDSBOROUGH, NORTH CAROLINA.

SWING.

SPECIFICATION forming part of Letters Patent No. 323,121, dated July 28, 1885.

Application filed October 18, 1884. (No model.)

To all whom it may concern:

Be it known that I, JOHN T. DEES, of Goldsborough, in the county of Wayne and State of North Carolina, have invented a new and Improved Swing, of which the following is a full, clear, and exact description.

The object of my invention is to provide a new and improved swing, which is so constructed that it can readily be operated by the person so occupying the swinging car, and which swing can be stopped very easily and rapidly.

The invention consists of the combinations of parts, including their construction, substantially as hereinafter fully set forth and claimed.

Reference is to be had to the accompanying drawings, forming part of this specification, in which similar letters of reference indicate corresponding parts in all the figures.

Figure 1 is a side view of my improved swing, parts being broken out and parts being in section. Fig. 2 is a sectional plan view. Fig. 3 is an enlarged detail longitudinal view of part of the car or box. Fig. 4 is an enlarged sectional view of my improved hanger.

From a base-frame, A, a series of inclined posts, B, project upward and toward each other and support a cross-bar, C, from which the swing is suspended. Two segmental tracks, D, having the concave edges toward the top, are secured to the posts B and to the base.

From the top cross-bar, C, a bar, E, is hung to swing by means of hangers F, and at the ends of the bar E eyebolts F' project from the side edges, to which eyebolts the upper ends of chains, cables, or wires G are secured, the lower ends of which are secured on the free ends of arm H of shafts J, journaled transversely in the end parts of the box, car, or cage K, the arms H being outside of the car.

Each shaft J is provided with an upwardly-projecting arm, L, within the car and at right angles to the arms H.

Each arm L is provided with a notch, M, for receiving the free end of a locking pawl or latch, I, pivoted to the car.

Each pair of ropes or wires G—that is, the ropes or wires at each end of the car—are united by a cross-piece, N, at about half the length, and to each piece N a rope or wire, O, is secured, which passes over a grooved pulley, P, in the end of a standard, P', or upwardly-pro-

jecting arm at the opposite end of the car, and is then fastened to one end of an elbow-lever, Q, pivoted on the same end of the car and 55 having a handle, Q', on its inner end.

From the bottom of the car, which is curved the same as the runners, two guards, R, project downward adjacent to the inner sides of 60 the curved tracks.

Small rollers S, adapted to run on the curved tracks, are journaled in the bottom of the car K.

In each rope or wire G a turn-buckle, W, is provided a few feet above the car, to permit of 65 tightening the ropes or wires, as may be necessary.

The hangers F are each formed of a heavy bolt, f, provided with a transverse aperture, g, having a recess, h, in its bottom for receiving a projection on the bottom of a pin, l, passed transversely through the aperture in the bolt, the said projection passing into the above-mentioned recess h, whereby the friction is reduced and easy working of the parts is 75 obtained. The pin l is secured at its ends in bolts m, secured in the bar E. A safety-rope, m', is passed through the bar E and through the top cross-piece, C, so that in case the hangers break the bar E cannot drop on the persons in the car. 80

To start and operate the swing, two persons at opposite ends of the car pull the levers Q upward alternately, and the ropes O pull on the cross-pieces N, thereby pulling the ropes 85 on wires G alternately toward each other. Thereby the center of gravity of the car is displaced alternately to opposite sides and the car begins to swing, first, slowly, and then more rapidly, and when once in full swing requires 90 but little power to operate it. When the swing is to stop, the arms L are disengaged from the latches I, and then swung down, whereby the arms H are swung up and the ropes G slackened slightly, thus permitting the car 95 to descend to the curved track D, upon which it rests, the rollers S running on the said tracks. The car runs down to the lowest points of the tracks and then comes to a standstill.

To operate the swing again, the arms L are swung up, thereby swinging the arms H down and drawing the ropes or wires G taut, whereby the car is raised sufficiently to clear the tracks. The arms L and the shafts J are 100

then locked in place by means of the latches or pawls I.

In case any of the parts break, the car cannot drop any farther than upon the tracks, 5 down which it slides.

Having thus described my invention, I claim as new and desire to secure by Letters Patent—

1. The combination, with a swing-frame, of segmental tracks held on the same, a swinging 10 car or box, and guards projecting from the bottom of the same at the sides of the tracks, substantially as herein shown and described.

2. The combination, with a swing-frame, of segmental tracks held on the same, a swinging 15 car or box, guards projecting downward from the same, and rollers journaled in the bottom of the car or box, substantially as herein shown and described.

3. In a swing, the combination, with a swing 20 car or box, of shafts journaled transversely in the same at the ends, arms on the ends of the shafts, to which arms the ends of the suspension ropes or wires are secured, a handle or arm for turning each shaft, and devices for 25 locking the shafts in place, substantially as herein shown and described.

4. In a swing, the combination, with a swing 30 car or box, of ropes or wires by which the car is suspended, a rocking elbow-lever at each end of the car, and a rope or wire secured to the elbow-lever and connected with the suspending ropes or wires at the opposite end of

the car, substantially as herein shown and described.

5. In a swing, the combination, with a swing- 35 ing car, of ropes or wires by which it is suspended, a rocking elbow-lever at each end of the car, a standard at each end of the car, a pulley on the top of each standard, a rope secured to each elbow-lever passed over the pulley on the top of the standard and connected with the opposite suspending ropes or wires, substantially as herein shown and described. 40

6. The combination, with a swing-frame, of the bar E, suspended from the cross-piece of the 45 frame by hangers, a car suspended from the bar E, and of a safety-rope, m', passed through the cross-piece C of the frame and through the bar E, substantially as herein shown and described. 50

7. In a swing, the combination, with the swinging car K, of the shafts J, having arms H, the arm L, having a notch, M, and the latch or pawl I for locking the arm L in place, substantially as herein shown and described. 55

8. In a swing, the combination, with the bolt f, having an aperture, g, having a recess, h, in its top, of the pin l, provided with a projection and held at its ends by bolts m, substantially as herein shown and described.

JOHN T. DEES.
